Charles H. Wilson

ATTORNEY

UNITED STATES PATENT OFFICE.

GABRIEL LANTIERI, OF JERSEY CITY, NEW JERSEY.

PERMANENT HAIR-WAVING MACHINE.

Application filed October 19, 1922. Serial No. 595,521.

To all whom it may concern:

Be it known that I, GABRIEL LANTIERI, residing at Jersey City, county of Hudson, and State of New Jersey, have invented certain new and useful Improvements in a Permanent Hair-Waving Machine, of which the following is a specification.

This invention relates to improvements in hair treating apparatus, and more particularly to machines adapted to be used for what is known as "permanent hair waving."

One of the objects of the invention is to provide a machine of the above character, which is simple in construction, and so constructed that the heating devices may be readily adjusted to the various positions required in their use in permanent hair waving, and whereby they may be removed to a position out of the way when not in use.

Another object of the invention is to provide a machine of the class described, wherein the electrical equipment is so constructed that it will not easily become disordered, and which may be operated or manipulated by an operator unskilled in the operation of electrical machines.

Other objects and aims of the invention, more or less specific than those referred to above, will be in part obvious and in part pointed out in the course of the following description of the elements, combinations, arrangements of parts and applications of principles, constituting the invention; and the scope of protection contemplated will be indicated in the appended claims.

In the accompanying drawings, wherein I have illustrated preferred forms of embodiment of my invention:

Figure 1 is an elevational view, showing my improved permanent hair waving machine, set up ready for operation.

Figure 2 is a top plan view, partly in section, the view being taken on line 2—2 of Figure 1, looking in the direction of the arrows.

Figure 3 is an elevational view of a portion of the machine constructed slightly different from that shown in Figure 1.

Figure 4 is a view in section, taken on line 4—4 of Figure 3.

Figure 5 is an elevational view, showing a slightly different form of embodiment of my invention.

Figure 6 is a view in section, showing a means for counterbalancing the heating devices; and

Figure 7 is a view in elevation, partly in section, showing a still different embodiment of my invention.

Referring now to the drawings, wherein similar reference characters refer to similar parts throughout the several views thereof, the reference numeral 1 denotes a suitable support, the same comprising a cylindrically formed tube or rod, adapted to be suspended from the ceiling after the manner of suspending chandeliers, through the lower end of which is attached, as by means of the threaded connection 2, a bracket 3, said bracket 3 having a depending flange portion 4. The flange portion 4 of the bracket 3 is provided with threaded lateral openings adapted to receive the inner end of the bracket arms 5, which bracket arms are bent or turned downwardly, as at 6, the lower ends of said arms extending through the upper and lower walls of a hollow ring-like structure 7.

The ring 7 is formed by two channel members 8 and 9, disposed in telescoping relation, suitable clamp nuts 10, 11 and 12 serving to hold the channel members 8 and 9 together, and to attach the ring 7 to the depending portions of the bracket arms 6. The ring 7 forms an outlet box for the various terminals, switches, and fuses which are associated with the heating elements and their supporting cables, presently to be described.

The ring 7 is in the present instance divided into four sections, each occupying an arc of 90°, and a circuit for each section is independently controlled, as by means of a switch 13, suitable fuses 14 and 15 being provided for the protection of each circuit. Each of the sections of the outlet box or ring 7 is in the present instance provided with a plurality of sockets 16, adapted to make connection between the line circuit and the cables connected with the heaters, and in the present instance one of the sockets is utilized for a tell-tale lamp 17.

The reference numeral 18 indicates the plugs which are adapted to connect with the socket 16, each plug in the present instance being connected with a cable 19. Each of the cables 19 is preferably divided at the point 20 into a pair of branch cables 21 and 22, and each of the latter cables is connected with one of the heaters 23.

Each of the cables 19 is supported intermediate its ends by a cord 24, which cord

passes upward over a pulley 25, thence outwardly and over a pulley 26, whence it passes downwardly, as at 27, the lower end carrying a counterbalancing weight 28. The 5 pulleys 25 and 26 are carried upon a laterally extending arm 29 of a bracket 30, depending from the ceiling, there being one of the arms provided for each supporting cord and the counterbalance weight.

10 The bracket arms 30 are so positioned relative to the standard 1, that the several heaters will be grouped together, as shown in Figure 1 of the drawings. The cords 24 are attached to the cables, as by means of 15 the pinch clamps 31, so that the positions of the heaters may be relatively adjusted with respect to the head of the subject being treated, it being understood that some of the heaters are adapted to be used on the top 20 portion of the head of the subject, and others upon the side portions thereof. The weight of the counterbalancing means 28 is such as to support the heaters in such a way that they will stay in their adjusted positions, whereby no strain will be put upon the 25 hair of the subject.

In the embodiment of my invention shown in Figure 3, there is provided a hollow ring 32, supported upon the bracket arms 33, from the hanger 1, and located in this hollow ring are take-up devices 34, adapted to receive the suspending cords 24, spring means 35 being provided in said take-up devices to act as counterbalancing means for the suspended heaters and their cables. The 30 take-up means 34 are supported by means of bracket arms 36 provided upon standards 37 fastened to the lower wall of the hollow ring 32.

40 In the embodiment of my invention shown in Figures 5 and 6, the take-up devices 38, similar to the take-up devices 34, are suspended upon arms 39, adjustably mounted upon the hanger 1.

45 In the embodiment of my invention shown in Figure 7, the take-up devices 40 for the suspending cords are carried in a box 41 carried by the bracket 42, which bracket is carried by the hanger 1, said bracket carrying the bracket arms 5, the remainder of the 50 construction being identical with that shown in Figures 1 and 2.

The heating devices 23 are preferably similar to those disclosed in my application 55 Serial Number 595,522, filed Oct. 19, 1922.

Having thus described my invention, the operation thereof, which should be largely understood, is as follows:—

60 The subject is seated beneath the machine and the hair suitably wound upon curlers and covered with the hair treating ingredients is inserted in the heaters, one curl being inserted in each heater, the position of the heaters being adjusted by the suspended cords 24, and by means of the pinch 65

clamps 31, whereby each heater may be individually adjusted to the exact position desired. When the machine is in operation this condition is disclosed by means of the tell-tale lamps 17.

70 It will accordingly be seen that I have provided a construction well adapted to attain, among others, all the ends and objects above sought, in a very simple yet efficient manner.

75 Having thus described my invention what I claim as new and desire to secure by Letters Patent is:

1. In a machine of the class described, in combination, a depending support having a 80 bracket at its lower end, a plurality of outwardly and downwardly extending arms carried by said bracket, a circular outlet box mounted upon the lower end of said arms, said outlet box being divided into a plurality of independent sections, each of which is provided with a plurality of terminals, a switch, and fuse members, a plurality of electric heaters adapted to lie in nested relation within the circumference of said outlet box, cables extending from said heaters to the terminals carried by said outlet box, and counterbalancing means for said heaters engaging said cables intermediate their ends.

85 2. In an apparatus of the class described, 90 in combination, a depending support, having a bracket at its lower end, a plurality of outwardly extending arms mounted upon said bracket, the outer ends of said arms having depending portions, a circular hollow ring forming an outlet box mounted upon the downwardly extending portions 95 of said arms, a plurality of electric heaters located within said ring, said ring being provided with a plurality of independent 100 sections, each section of which is provided with a plurality of terminals, a switch, fuse members, cables connecting said heaters with the terminals of said outlet box, and adjustable counterbalancing means adjustably connected with the intermediate portions of said cables.

105 3. In an apparatus of the class described, 110 in combination, a depending support, having a bracket at its lower end, a plurality of outwardly extending arms mounted upon said bracket, the outer ends of said arms having depending portions, a circular hollow ring forming an outlet box mounted upon the downwardly extending portions of said arms, a plurality of electric heaters located within said arms, a plurality of electric heaters located within said ring, said ring being provided with a plurality of independent sections, each section of which is provided with a plurality of terminals, a switch, and fuse members, cables connecting said heaters with the terminals of said outlet box, adjustable counterbalancing means 115 adjustably connected with the intermediate 120 portions of said cables.

portions of said cables, and depending supporting means, independent of said first named supporting member, for said counter-balancing means.

- 5 4. In a machine of the class described, in combination, a depending support, a continuous circular hollow outlet box carried by the support, said outlet box having internal partitions dividing the same into a plurality of 10 sections, terminals and fuses arranged in each of the said sections, a switch in each

section, a plurality of heaters suspended below the said box, and take-up devices in each of the said sections of the outlet box for independently and adjustably suspending the 15 said heaters with respect to the said box.

In testimony whereof, I affix my signature in the presence of two witnesses.

GABRIEL LANTIERI.
